(No Model.)

A. MCKAY.
SADDLE TREE.

No. 403,129.

Patented May 14, 1889.

L. J. Beaumont

Andrew McKay,
by John Shinn, Attorney

UNITED STATES PATENT OFFICE.

ANDREW MCKAY, OF PHILADELPHIA, PENNSYLVANIA.

SADDLE-TREE.

SPECIFICATION forming part of Letters Patent No. 403,129, dated May 14, 1889.

Application filed December 31, 1888. Serial No. 295,080. (No model.)

To all whom it may concern:

Be it known that I, ANDREW MCKAY, a citizen of the United States, residing at Philadelphia, in the county of Philadelphia and State 5 of Pennsylvania, have invented a new and useful Improvement in Saddle-Trees, of which the following is a specification.

My improvement relates to saddle-trees, or the frame upon which a harness or riding saddle is built.

The object of my improvement is the construction of a frame or tree that may be adjusted so as to fit the size and shape of the backs of different horses and mules; also, to 15 arrangements for connecting the "back-band" to the saddle-tree and permitting the back-band to freely slide over the top when the horse or mule is in motion.

My invention consists, first, in constructing 20 the saddle-tree with a joint at the top and connecting the two sides by a right and left hand regulating-screw; second, constructing the sides with slots and cross-bars, so as to connect the back-band to the frame or tree in 25 such a manner as will permit the back-band to freely slide over the top of the frame when the horse or mule is in motion.

My improved saddle-tree is constructed as 30 shown in the accompanying drawings, in which—

Figure 1 is a front view of a saddle-tree constructed according to my improvements. Fig. 2 is a side view. Fig. 3 is a vertical section taken on the line X Y of Fig. 2. Fig. 4 is an 35 edge and side view of one of the nut-caps. Figs. 5 and 6 are side and edge views of the cross-bars. Figs. 7, 8, 9, and 10 are views of the joint-block. Figs. 11, 12, and 13 are views of the regulating screws and nuts. Figs. 14 40 and 15 are views of the "post." Figs. 16, 17, and 18 are views of the "crupper-loop."

Similar letters refer to similar parts throughout the several views.

The parts I prefer to be all made of a non- 45 corrosive metal, or the parts may be galvanized. The block A is cast in the shape shown in Figs. 7, 8, 9, and 10, and having triangle-shaped slots a at each end. The hole b may be cast in, or it may be drilled.

50 B is a bolt having a six-sided nut on each end.

C is the shell forming the sides, and is cast

to the joints D. This shell is cast with slots d d and a recess, E, for the back-band, which recess is in line with the notch F in the joint-block A.

G is a cross-bar having at each end a button-head, e.

H is a regulating-screw. On one end is cut a right-hand screw-thread; on the other a left-hand thread.

J are nuts, which nuts are each provided with pivot-pins K.

P is a cap which is fitted for the pins K on the nuts J. The cap P is fastened to the shell 65 C by rivets, as shown in Fig. 2.

The shell C has cast or drilled in it a series of small holes. (See Fig. 2.) These holes are for rivets that are used to rivet the leather and other coverings to the frame or tree. 70

R is the post. The lower part is made triangle shape and to fit the hole a in joint-block A. The lower part of the post R is provided with a slotted hole, g, for the joint-bolt B.

S is the crupper-loop. The lower part of 75 this loop is made triangle shape and to fit the hole a in block A, and the lower part is provided with a slotted hole, g, for the joint-bolt B.

My improved saddle-tree is put together 80 and made ready for use in the following manner: The block A is placed between the joints D D. The post R and crupper-loop S are inserted in the openings a a. The bolt B is passed through the holes in joint D, loop S, 85 block A, post R, and joint D, when the nuts are put on the bolt B. The regulating-screw is then put in place, as shown in Fig. 3, when the caps P are riveted to the shell C. The bars G are by the button-heads e e connected 90 to the shell C. The shanks of the button-heads are free to slide up and down in the slots d d. The leather and other coverings are put on the frame, when the back-band is slipped under the bar G and over the block 95 A in the notch F and under the bar G on the other side.

When the saddle is to be fitted to the horse's or mule's back, the screw H is turned to open or close the sides until the padding on the inside of the frame fits the back, when the nuts on the bolt B are screwed tight and hold the saddle to a fit.

When the saddle is placed on a horse's back

and the back-band is connected to the shafts, the motion of the horse will cause the back-band to have a sliding motion over the top in the notch F, and the band, being under the 5 bars G, will be confined to the recess E. The button-heads e e keep the bars to the shell C. The shanks of the button-heads slide in the slots d d.

Having above described my invention and 10 the manner of constructing and using the same, what I claim as my invention is—

1. A saddle-tree consisting of the block A, cut away centrally at the top and bottom and provided at each end with the vertical 15 triangular holes and a longitudinal bore, the check-hook and crupper-loop having the triangular posts adapted to fit in the triangular

openings in the block, the sides C C, provided with bearings D D, and rod B, having a nut at each end and adapted to hold the several 20 parts together, substantially as set forth.

2. A saddle-tree consisting of the block A, check-hook R, crupper-loop S, and sides C C, secured together substantially as set forth, said sides having the slots d d, in which the 25 button-heads of the cross-bars G are fitted, said cross-bars and the right and left adjusting-screw fitted in pivoted nut-bearings in the sides C C, said bearings secured in the sides by the caps P, substantially as set forth.

ANDREW MCKAY.
